UNITED STATES PATENT OFFICE.

GEORGE O. ALLEN, OF MONTVILLE, CONNECTICUT.

WIRE-STRETCHING IMPLEMENT.

SPECIFICATION forming part of Letters Patent No. 364,564, dated June 7, 1887.

Application filed April 11, 1887. Serial No. 234,355. (No model.)

To all whom it may concern:

Be it known that I, GEORGE O. ALLEN, a citizen of the United States, residing at Montville, in the county of New London and State 5 of Connecticut, have invented a certain new and useful Improvement in Wire-Stretching Implements, which improvement is fully set forth and described in the following specification, reference being had to the accompanying 10 sheet of drawings, in which—

Figure 1 illustrates the manner in which my said implement is used in the act of wiring packing-cases. Fig. 2 is an enlarged side view of said implement, and Fig. 3 a front end view 15 of the same.

My invention is in the class of tools specially adapted for grasping and stretching wire, hoop-iron, wire screen, &c., and has for its immediate objects the production of a 20 portable tool of moderate cost and great leverage, in which the gripping power of the jaws will be proportionate to the applied leverage, and whose notched jaws shall be capable of biting or gripping the wire sufficiently 25 to prevent its slipping without cutting or otherwise severing said wire. Said implement is especially useful in strapping or wiring packing-cases, and by its adoption common annealed wire of single strand may be 30 used successfully in place of hoop-iron, and of twisted wire, as more recently used.

Referring to the drawings, the letter *a* indicates the handle of said implement, having an integral jaw, *a'*, at the opposite end, and 35 having pivoted thereto a companion jaw, *b*, having a projection, *b'*, at approximately a right angle to the handle *a*. The jaws *a' b* are held normally in an open position by a spring, which may be applied in any of the 40 several ways common to this class of tools. I have here shown a flat spring, *c*, secured to handle *a*, the free end of said spring bearing in a slot in the rear side of the projection *b'*.

The jaws *a' b* project a considerable distance laterally in each direction, (see Fig. 3,) 45 so that the wire to be stretched may pass through and be held by said jaws in a direction substantially parallel with the handle *a*, as will be understood by reference to Fig. 1. Said jaws are notched or channeled in a direction 50 transverse to the line of wire to be held, as at *e*, and at the outer edge of each jaw is left a rib, *d*, with flat face, to prevent the jaws from coming into such close contact with each

other as to bite the wire completely in two. 55 These ribs *d* form an important feature of my invention.

When about to strap a case, one end of the wire is secured in place by a staple driven over it. Said wire is then passed across the 60 end of the case, and is grasped between the jaws *a' b*, the projection *b'* resting meanwhile against the vertical side of the case, as shown in Fig. 1. Now, by forcing the handle *a* downward, the wire is drawn tightly across 65 the box, and may be fastened by staples or double-pointed tacks, which straddle the wire.

The construction of my implement is such that an increase of pressure on lever *a* furnishes a proportionate increase of gripping 70 power in the jaws, so that the wire cannot slip. For cases where it is desirable to grip the wire between the corners of a case, I provide a spur, *h*, at the end of projection *b'*, which may be driven into the wood to prevent 75 the tool from slipping in the act of stretching the wire. I have also provided a second spur, *i*, on the side of projection *b'*, which may be used in the end of a case. These spurs add but slightly to the cost of construction, but add 80 materially to the convenience and completeness of the implement.

Having thus described my invention and the manner in which it is to be operated, I claim as new and wish to secure by Letters 85 Patent—

1. In combination with a handle having one end formed as a laterally-projecting jaw, a corresponding jaw pivoted thereto, and having the lever-arm *b'*, projecting therefrom in a 90 direction approximating a right angle, the coincident faces of the said jaws being formed with gripping-teeth *e* and stops *d*, substantially as and for the objects specified.

2. In combination with a handle having 95 one end formed as a laterally-projecting jaw, a corresponding jaw pivoted thereto, and having the lever-arm *b'*, terminating in a spur, *h*, projecting therefrom in a direction approximating a right angle, the coincident faces of 100 said jaws being formed with both gripping-teeth and stops, substantially as and for the objects specified.

GEORGE O. ALLEN.
